UNITED STATES PATENT OFFICE.

NATHANIEL SHEPARD KEITH, OF PHILADELPHIA, PENNSYLVANIA; CLAUDE L. ROTH,
ADMINISTRATOR OF THE SAID NATHANIEL SHEPARD KEITH, DECEASED.

AMALGAMATOR.

Application filed April 21, 1924. Serial No. 707,810.

My invention relates to improvements in amalgamators of the kind useful for extracting precious metals, especially gold, from a flowing pulp of comminuted ore 5 mixed with water to which mercury has been added either during or after a milling, grinding or concentration process.

Although amalgamators of a revolvable type have been used with some success in 10 the treatment of pulverized ores, the conditions under which most of them operate cause the mercury to be broken up and oxidized with the result that much mercury is lost, especially when pressure is used in 15 addition to the force of gravity to pass the metalliferous pulp through a large mass of mercury. Furthermore, the precious metals in such ores are often in such fine particles or so flattened that they tend to float over 20 the amalgamating surface without coming in contact with same or the metallic particles are so rusty or coated with impurities that they will not amalgamate readily.

The object of my invention is to provide a 25 machine and process whereby a large quantity of metalliferous pulp, to which mercury has been added, can be rapidly and cheaply brought into contact with an extensive amalgamating surface, by means of centrifugal 30 force in the presence of nascent hydrogen, produced by electrolysis of the water, without using any pressure except centrifugal force and the force of gravity to pass the pulp over said surface so that the machine 35 will have greater capacity and efficiency with less loss of mercury than other machines in common use.

I attain said object by applying said 40 forces and an electrical current to such pulp containing mercury by means of a novel apparatus, the chief features of which are a rotatable, vertical shaft carrying concentrically a disc having a boss around said shaft; a hollow, vertical cylinder held to 45 said disc by said boss and by compression of a cap holding the top of said cylinder rigidly to said shaft; a tube of lead covering said cylinder but insulated therefrom and from 50 said disc and cap; encircling said tube, an annular cup bolted to said disc but elevated therefrom by adjustable washers; a removable vertical cylinder with an inner surface 55 of copper and a serrated bottom resting in said cup and guyed to said disc and an insulated ring near the top of said shaft con-

nected by conducting wire with said tube of lead and means for rotating said parts as a unit and supplying pulp containing mercury to the annular space between said cylinders and passing an electrical current 60 to said ring and taking it up from said outer cylinder when said pulp is passing through the machine. The electrical current is used to produce nascent hydrogen at the amalgamating surface to preserve the brightness and receptive properties of the mercury. 65

The apparatus is made operative by means of other devices combined with said fundamental features which I will now describe by explaining the construction and manner 70 of using a simple form of machine embodying my invention and referring to the accompanying drawings illustrating the same in which like letters of reference are used to denote like parts of the apparatus, except 75 as otherwise noted.

Figure 1 represents a vertical sectional view of the rotating parts of such machine and its bearings, without showing the lateral supports or electrical connections. 80

Figure 2 is a view in which the lower parts of the cylinder and cup are relatively displaced, the former being shown in elevation, and the latter being shown in cross-section and illustrates the manner in which 85 the bottom of said cylinder must be serrated to allow any excess of mercury or amalgam on the inner surface of said cylinder to be caught in said cup, which could not be as readily shown in Figure 1 without 90 causing confusion in the lines thereof.

Figure 3 represents a plan view and Figure 4 a vertical view on an enlarged scale 95 of the lower portions of the outer and inner cylinders and the annular cup and the disc by which they are supported respectively and the bolts and springs for keeping the outer cylinder in place while being rotated with the other parts aforesaid. Figure 4 also shows how the tube of lead surrounding 100 the inner cylinder must be insulated therefrom and from said disc.

Figure 5 represents a top view of such machine when supported by a framework not shown in the previous figures without 105 showing the clamp and wires needed for electrical connection.

Figure 6 represents a broken vertical section of the upper and lower portions of the machine when set in such a framework, not 110

- including certain parts shown in Figure 4 or the bearing beneath the disc shown in Figure 1 which bearing is to be supported by arms like the one shown beneath the pulley in Figure 6, bolted to a cross-bar extending to uprights at equal distances from the centre line of the shaft. This figure shows also the manner of making the electrical connections and introducing the pulp.
- 5 In all the figures, A represents a rotatable vertical shaft, preferably of steel, to be revolved in bearings at the top, bottom and intermediate points marked with the letters B¹, B, B, B respectively as shown in Figure 1. The top bearing must be removable and should be made with arms like a spider to be bolted to the upright supports of an outer frame shown in Figures 5 and 6 only. The intermediate bearings are not essential to the working of the machine except for the purpose of relieving strains on other parts and decreasing any tendency to oscillation. The shaft and all parts affixed thereto may be turned at any desired speed by means of a pulley C fastened on said shaft and driven by a belt connected with a suitable source of power not shown. The bearing B at the bottom of the shaft must be set in a solid base from which vertical supports must be extended to projections of the top bearing B¹ as shown in Figure 6. All bearings should be provided with bushings which are not always shown in the drawings.
- 35 D refers to the circular disc aforesaid, preferably made of metal, which must be fastened concentrically to the shaft A and is intended to support at some distance above it the concentric annular cup E through the medium of washers L, preferably of insulating material, through which are passed bolts K so as to leave spaces Z as outlets for the pulp to flow from the machine which outflow may be regulated by inserting or removing washers, but said outlets must not be increased to such an extent that the machine cannot be kept filled with pulp when rotated at a speed which would otherwise insure amalgamation.
- 50 F refers to a copper cylinder supported concentrically in a vertical position by the annular cup E in which the bottom of said cylinder rests at a sufficient distance from the inner edge of said cup to allow any mercury or amalgam descending on the inner surface of said cylinder to pass through numerous serrations at the bottom thereof denoted by f in Figure 2, so that the cup in combination with the serrated cylinder forms a trap to retain such mercury and amalgam until it is convenient to remove same therefrom, which may be done more frequently than the cleaning up of the amalgamating surface of said cylinder without much interruption to operations.

M refers to a smaller hollow cylinder surrounding the shaft A concentrically at some distance therefrom within the cylinder F and fastened rigidly by compression to the disc D around a circular boss extending outward from the shaft to any desired points indicated by the letters d, d in Figures 1 and 4, by screwing tight a nut O on the shaft A against the cap N inserted in the top of the cylinder M, for which purpose said shaft must be threaded for some distance above said cap as shown in Figure 6.

P refers to a tube or covering of lead to be placed around the cylinder M except at the ends thereof, at such distance from said cylinder and said ends as will permit sufficient insulating material, such as melted asphalt, to be introduced between said lead and said cylinder and the metals adjacent to the end thereof to prevent any passage of electrical current from said lead as an anode to the outer cylinder F as a cathode in an electrical circuit except through the pulp as an electrolyte. The word, "insulation" is used in some of the figures to mark the space to be left for that purpose.

R refers to a removable ring or two-piece clamp to be affixed to the shaft A but insulated therefrom and to be connected with electric conducting wires with the lead tube or casing P to make the latter an anode when a carbon electric brush connected with the positive pole of a source of electricity is caused to bear against the periphery of said ring or clamp while another such brush connected with the negative pole is caused to bear against the outside or upper edge of the outer cylinder F in such a manner that its inner surface of copper will act as a cathode in an electrolytic circuit, during the operation of the apparatus.

G denotes the springs for holding the outer cylinder F in place by means of stay bolts H on said cylinder and like bolts I on said disc D.

S refers to upright parts of the framework supporting the working parts of the apparatus and T to cross bars for holding the intermediate bearings B, B, firmly in position and U to angle irons for joining the upright supports to the base of the machine.

X is a chute or launder for introducing the pulp in an obvious manner and Z refers to the spaces between the disc D and cup E divided by said bolted washers L through which it must flow out of the machine.

To operate the machine it is first started rotating and then a stream of pulp is allowed to flow in the annular space between the two revolving cylinders F and M until said space is practically filled with pulp after which the pulp must not be allowed to flow in faster than it is discharged from the machine through the outlet space Z,

which can be regulated as aforesaid to conform to the speed of rotation most suitable for amalgamation.

It is obvious that the revolving parts of the machine must be rotated at sufficient speed to make the centrifugal force of their movement operate to bring the mercury and metals to be recovered from the pulp in contact with the copper amalgamating surface before the force of gravity takes such material through the machine and persons skilled in the art of amalgamating can readily determine what speed is necessary by observing the effect on said surface.

15 The amount of mercury added to the pulp should be kept as low as possible without impairing the efficiency of the machine. A quantity equal to three times the weight of precious metal in the ore should be sufficient, 20 that is to say for each ounce of gold to the ton of ore in the pulp three ounces of mercury should be added thereto in the launder X, if not introduced in a previous operation. As the pulp in which minute particles of 25 precious metal are suspended or floating passes between said cylinders, each particle is impelled through the pulp by the centrifugal force of rotation toward the copper amalgamating surface proportionately to its 30 specific gravity with respect to other particles and the mercury being the most liquid and dense will most rapidly reach said surface and having the property of forming an amalgam with copper will adhere thereto 35 and absorb the particles of other metals impelled against such surface if they are capable of being amalgamated or wetted by the mercury. Particles which will not amalgamate will be displaced by the swirling 40 action of the pulp and carried out of the machine. Mercury which remains liquid will tend to pass down said surface into the annular cup E while mercury accumulating precious metals will adhere to the amalgamating surface in a gradually hardening 45 coat which must be removed by "cleaning up" from time to time as the affinity of the mercury for precious metals is satisfied.

To clean up, first stop the flow of pulp 50 and allow the pulp in the machine to run out. Then stop the machine and remove the topmost bearing B' by lifting it off the shaft and detach the electrical brushes from the ring R and cylinder F. Then free the cylinder F by releasing the springs G and remove said cylinder. To save time in operating, a like cylinder may be put in its place 55 and the said bearing and electrical connections replaced without waiting for the cylinder carrying amalgam to be cleaned in the manner well known to the art.

It will be manifest to those skilled in mechanics, after understanding my invention, 60 that modifications and substitutions of equivalents may be made in the manner of

construction and materials to be used in forming and operating an apparatus of the kind I have described without departing from the spirit or scope of my invention and that it is not to be limited to the particular apparatus described.

While the relative positions and dimensions of the various parts of an apparatus intended to apply my process may vary somewhat from those indicated by my drawings, I should say that in order to be effective there must be no change that will destroy the function for which I have designed any such parts and that the space between the two cylinders should not be less than one-tenth or more than three-tenths of the diameter of the outer cylinder and that the height of the cylinders should not be less than said diameter or exceed four times the same for obvious reasons.

I claim as my invention:—

1. In an amalgamating machine, the combination consisting of a rotatable, vertical shaft carrying concentrically a disc having a boss around said shaft; a hollow, vertical cylinder held to said disc by said boss and by compression of a cap holding the top of said cylinder rigidly to said shaft; a tube of lead covering said cylinder, but insulated therefrom and from said disc and cap; encircling said tube, an annular cup bolted to said disc but elevated therefrom by adjustable washers; a removable vertical cylinder with an inner surface of copper and a serrated bottom resting in said cup and guyed to said disc and an insulated ring near the top of said shaft connected by conducting wire with said tube of lead and means for rotating said parts as a unit and supplying pulp containing mercury to the annular space between said cylinders and passing an electrical current to said ring and taking it up from said outer cylinder when said pulp is passing through the machine.

2. In an amalgamating machine, the combination of a rotatable, vertical shaft, a disc carried thereby, a vertically arranged inner cylinder carried by said disc, a tube of lead surrounding said cylinder, a compression cap for holding said inner cylinder rigidly to said shaft, an outer cylindrical cover of copper with a serrated bottom edge which cover surrounds said cylinder, a member having an annular recess secured upon said disc and within which recess said serrated edge is positioned, an insulated ring carried by said shaft, an electrical conductor between said covering of lead and said ring, means for supplying pulp containing mercury to said outer cylinder, means for rotating said shaft, and means for passing an electrical current to said ring and taking up said current from said outer cylinder.

3. In an amalgamating machine, the com-

1
bination of a rotatable, vertical shaft, a disc carried thereby, a vertically arranged inner cylinder carried by said disc, a tube of lead surrounding said cylinder, a compression cap for holding said inner cylinder rigidly to said shaft, an outer cylindrical cover of copper with a serrated bottom edge which cover surrounds said cylinder, means for resiliently securing the lower part of said outer cylinder to said disc, a member having an annular recess secured upon said disc and within which recess said serrated edge is positioned, an insulated ring carried by said shaft, an electrical conductor between said covering of lead and said ring, means for supplying pulp containing mercury to said outer cylinder, means for rotating said shaft, and means for passing an electrical current to said ring and taking up said current from said outer cylinder.

4. In an amalgamating machine, the combination of a rotatable, vertical shaft, a disc

carried thereby, a vertically arranged inner cylinder carried by said disc, a tube of lead surrounding said cylinder, a compression cap for holding said inner cylinder rigidly to said shaft, an outer cylindrical cover of copper with a serrated bottom edge which cover surrounds said cylinder, a member having an annular recess secured upon said disc and within which recess said serrated edge is positioned, an insulated ring carried by said shaft, above said cylindrical cover and inner cylinder, an electrical conductor between said covering of lead and said ring, means for supplying pulp containing mercury to said outer cylinder, means for rotating said shaft, and means for passing an electrical current to said ring and taking up said current from said outer cylinder.

In testimony whereof I affix my signature.

NATHANIEL S. KEITH.
